UNITED STATES PATENT OFFICE.

WILLIAM WESLEY WELLS, OF SANDY HILL, NEW YORK.

PAPER-MAKING MACHINERY.

SPECIFICATION forming part of Letters Patent No. 611,303, dated September 27, 1898.

Application filed March 16, 1898. Serial No. 674,054. (No model.)

To all whom it may concern:

Be it known that I, WILLIAM WESLEY WELLS, a citizen of the United States, residing at Sandy Hill, in the county of Washington and State of New York, have invented 5 certain new and useful Improvements in Paper-Making Machinery; and I do hereby declare the following to be a full, clear, and exact description of the invention, such as will 10 enable others skilled in the art to which it appertains to make and use the same.

My invention relates to certain new and useful improvements in paper-making machinery, and particularly to the construction 15 of a beater for imparting a succession of blows to the traveling conveyer-felt at some point in its path of movement intermediate between that at which it delivers the pulp-film to the winding-roll and that at which it 20 again receives a supply from the film-making roll. The purpose of this beater, coöperating with a water-jet, is to detach from the conveyer-felt any particles of wood fiber that may have adhered thereto after passing the 25 winding-roll, so that the felt will always present a clean and unobstructed smooth surface as it comes into operation at the film-making roll.

In the accompanying drawings, Figure 1 30 represents a side elevation of a machine embodying my invention. Fig. 2 represents a plan view, partly in section, of my improved beater. Fig. 3 represents a side elevation of 35 one of the beater-bar spiders and illustrates the means employed for securing the beater-bars therein. Fig. 4 represents an edge view of one of said spiders, and Fig. 5 represents a partial longitudinal section showing one of the spiders keyed upon the beater-shaft.

Similar letters of reference indicate similar 40 parts throughout the several views.

Referring to the drawings, *a* indicates the vat, which receives the paper-stock, and *b* the suction-roll, of the usual character, upon 45 which the paper-film is formed and from which it passes to the conveyer-felt *c* and thence to the pressure-roll *d*, upon which it is wound until a "blanket" of the desired thickness is formed and detached, as is well understood 50 in the art.

After delivering the paper-film to the winding-roll *d* the conveyer-felt *c* on its return

travel to the film-roll passes my improved beater, which is provided with a shaft *e*, 55 driven by the pulley *h* or the like, and mounted in suitable bearings, as shown. Upon the shaft *e* are arranged at convenient distances apart a series of spiders having hubs *f*, provided with keyways *f'*, whereby they are adapted to be keyed or splined to the shaft, 60 as indicated by the key *f''* in Fig. 5. In order still further to insure their absolute rigidity upon the shaft, the hubs are provided with set-screws, as *g*, adapted to be screwed up into powerful binding contact with the 65 shaft.

Each spider constitutes an integral casting in the construction shown and is provided with radial arms *m*, forked at their outer ends and provided thereat with recesses *n* for 70 the reception of tubular beater-bars *s*. It will be observed that the contour of the recesses *n* is such that the tubular beater-bars must be inserted longitudinally in order to enter them, in which position they are overlapped beyond their longitudinal centers by the forked arms, as clearly appears in Fig. 3. The tubes are therefore held securely against 75 all danger of being thrown out of the recesses *n* by centrifugal force and require no additional securing devices for that purpose. To guard against their longitudinal shifting, however, pins *r* pass through the forked ends and through the tubes; but even these are unnecessary for the intermediate spiders. 80

On reference to Fig. 1 it will be noted that the beater-bars bear such a relation to the conveyer-felt as to impart to the latter a succession of impact-blows at a point immediately adjacent to the water-jet, whereby any 90 adhering wood fibers are loosened and detached from the felt on its return travel to the suction-roll.

Should any of the bars require replacement or repair, this may be readily effected 95 by removing the retaining-pins and sliding the bar in question longitudinally from the recesses. When the impact surface of the bars becomes worn, it is merely necessary to remove the pins *r* and revolve the bars within 100 their bearings in the spiders sufficiently to present a new impact surface. Where the bars are cylindrical, this may be done without removing them at all from their bearings in

the spiders. The duration of available use of the beater-bars is correspondingly multiplied by the number of new surfaces which can thus be successively employed.

5 Having thus described my invention, what I claim is—

1. A beater for paper machinery, comprising a shaft, spiders mounted upon the shaft and provided at their outer ends with forked arms forming beater-bar recesses, and beater-bars revoluble within said recesses, the contour of the recesses being such that the forked arms overlap the beater-bars and hold them against centrifugal expulsion.

10 2. A beater for paper-making machinery, comprising a shaft, spiders mounted upon the shaft and provided at their outer ends with forked arms forming beater-bar recesses, and beater-bars revoluble within said recesses,

the beater-bars being cylindrical and the recesses being greater than a semicylinder.

15 3. A beater for paper-making machinery, comprising a shaft, spiders mounted upon the shaft and provided at their outer ends with forked arms forming beater-bar recesses, 25 and beater-bars revoluble within said recesses, the contour of the recesses being such that the forked arms overlap the beater-bars and hold them against centrifugal expulsion, and pins passing through the forked arms and 30 beater-bars, to prevent the latter from shifting longitudinally.

In testimony whereof I affix my signature in presence of two witnesses.

WILLIAM WESLEY WELLS.
